JAMES M. SCHOONMAKER, OF PITTSBURG, PENNSYLVANIA.

Design No. 2,827, dated November 5, 1867.

DESIGN FOR A TRADE-MARK.

The Schedule referred to in these Letters Patent and making part of the same.

TO ALL WHOM IT MAY CONCERN:

Be it known that I, JAMES M. SCHOONMAKER, of the city of Pittsburg, in the county of Allegheny, and State of Pennsylvania, have originated and designed a new Design for a Trade-Mark, of which the following is a full, clear, and exact description, reference being had to the accompanying specimens or drawings, making a part of this specification.

My improved design for a trade-mark consists in a colored background or field, surrounded by an ornamental border, and at or near the centre of which is printed in colors a view of the national flag unfurled. Around this flag are arranged the words "Banner Pure White Lead," printed in large letters and colored, the word "Banner" being near the upper left-hand corner, the word "Pure" near the lower right-hand corner, and the words "White Lead" under the whole, and extending across the lower part of the design.

What I claim as my invention, and desire to secure by Letters Patent, is—
The design for a trade-mark herein set forth and shown.

In testimony whereof I, the said JAMES M. SCHOONMAKER, have hereunto set my hand.
